UNITED STATES PATENT OFFICE.

PHILIP MUELLER, OF DECATUR, ILLINOIS, ASSIGNOR TO ADOLPH MUELLER, TRUSTEE, OF DECATUR, ILLINOIS.

WATER-SUPPLY FIXTURE.

Application filed November 12, 1919. Serial No. 337,482.

To all whom it may concern:

Be it known that I, PHILIP MUELLER, a citizen of the United States, residing at Decatur, in the county of Macon and State 5 of Illinois, have invented new and useful Improvements in Water-Supply Fixtures, of which the following is a specification.

This invention relates to water supply fixtures and has for its object to provide a 10 fixture in which a cock for basin or sink supply will be provided, which cock will also control the flow to a spray device, and coupled with this cock for basin and spray discharge will be the hot and cold water faucets of any desired type.

In the drawings herewith I have illustrated two embodiments of the invention, and in said drawings:—

Figure 1 is view in front elevation of one 20 embodiment of the fixture.

Figure 2 is a view in elevation of the fixture shown in Figure 1 taken from the side.

Figure 3 is a sectional view taken vertically through the center cock and mixing 25 chamber to which it is connected.

Figures 4, 5 and 6, are views similar to Figures 1, 2 and 3 respectively, and shows another embodiment of my invention.

In the drawings, I have shown for illustrative purposes only, my invention embodied in barber's fixtures and in these drawings like members indicate like parts in the several views. 10 designates faucets of not unusual construction, and if desired 30 either a faucet of the Fuller type or one of the quick compression type may be employed.

The faucets 10 are located at any convenient distance from each other on the 40 basin slab, and one of them is connected in the usual manner to a suitable hot water supply and the other to a cold water supply. Extending from the faucets 10 are supply pipes 11 which deliver to a union 45 or mixing chamber.

The supply pipes 11 may be connected to the faucets 10 in any suitable manner, but, preferably, to prevent rotation of the pipes, they are threaded into screw-threaded openings in ball elbows on top of the faucets.

In the embodiment of my invention illustrated in Figures 1 to 3, the supply pipes 11 deliver to a mixing chamber 12 to which is connected, by means of a short outwardly

extending neck 13, a center cock 14. In 55 these figures the mixing chamber 12, the cock body 15 and the neck section 13 are embodied in a single casting which is divided into two chambers by a horizontally disposed partition 16 having an opening 60 which is flared downwardly to provide a conical valve seat 17. The supply pipes 11 deliver to the mixing chamber or union 12 beneath the partition 16. The cock 14 has, in registry with the opening or valve seat 65 17, a downwardly projecting basin or sink spout or nozzle 18 having, at its upper end, a valve seat 19.

In the rear wall of the mixing chamber and above the partition 16 is a discharge 70 opening which receives a nipple 20 to which is connected a rubber tube 21 leading to a spray device 22.

The center cock is provided with a control device, preferably a push-rod 23, passing through the usual packing in the upper end of the neck of the cock, and having swiveled to its lower end a double-headed ball valve 24. The opposite ends of this valve are adapted to engage the valve seats 75 19 and 17 to control the flow of water to the basin nozzle 18 and the spray nipple 20. The valve 24 is so constructed that, when forced downwardly it will engage the seat 19 to close the passage leading through 80 the basin delivery spout 18 and permit the water to flow through the valve seat 17 to the nipple 20. When the valve is pulled upwardly, it will close the passage leading to the spray delivery connection 20 and permit discharge from the basin nozzle 18.

In the embodiment of my invention, disclosed in Figures 4, 5 and 6, I have illustrated a slightly different construction, in that the mixing chamber 12', the cock body 15' and the neck section 13', are each formed separately and connected together by suitable means, such as screw-threads. In this embodiment, the union 12' has a single undivided chamber, and the neck portion 13' 95 comprises a pipe section having a single undivided through passage. The cock 14' is divided into two chambers by a horizontally disposed partition 16', having an opening 100 forming a valve seat 17'. The neck portion 13' discharges into the valve chamber below partition 16', and the upper chamber 11 is provided with a discharge opening which 105

receives the nipple 20' to which is connected the rubber tube 21.

In the construction shown in Figs. 4, 5, and 6, it will be readily seen that when the valve 24 is in engagement with the valve seat 19 of the spout 18, the water is permitted to flow through the valve seat 17', chamber 41 and the nipple 20' to the spray head 22. When the head 24 is in engagement with the seat 17', the water will discharge through the basin spout 18.

From the foregoing, it will be seen that the faucets 10 controlling the hot and cold water supply may be manipulated in the usual manner and will deliver to the mixing chamber 12 or 12'; and from said chamber the commingled hot and cold water will flow by the connection 13 or 13', in which it is further mixed to the center cock 14 or 14', from which it will be delivered in proper condition to the basin or spray nozzles, dependent on the position of the valve 24.

By delivering the hot and cold water to a mixing chamber and leading it from said chamber through a waterway to the center cock, instead of delivering it directly to the valve chamber of the center cock as has been proposed in some constructions now in use, I insure the proper mixing and tempering of the water and avoid the objectionable alternating or initial dashes of hot or cold water which occur where the delivery from the supplies is directly to the valve chamber of the center cock. In other words, there is ample opportunity, during the flow of the hot and cold water from their respective faucets to the center cock or point of delivery for them to blend and mingle and give a proper mixture.

The hose or tube 21 carrying the spray device 22 is supported adjacent the mixing cock valve so that the hand which operates the hose may also be employed to adjust the valve. In the preferred construction illustrated, the hose passes from the nipple 20 through a bracket 36 secured to the standard 37, removably mounted on and rising vertically from the mixing chamber of the fixture, said standard having at its upper end an open retaining fork 38 through which the hose 21 may be passed. A second fork 39 mounted on the standard 37 and preferably formed integrally with the said bracket 36 is provided to receive the hose 21 and retain the hose and head in the position shown in Figure 1. Preferably the fork 38 will be provided with a saddle 40 to support the hose 21 in order to prevent abrupt bending and wearing of the hose. The hose is thus connected to the fixture so as to be supported adjacent the mixing valve, which, having an operating handle of the push-rod type, may be adjusted by the same hand that operates the hose with-

out laterally directing the spray, as would occur in the actuation of a rotating or swinging handle.

It is of course understood that in the present disclosure I have shown my invention embodied in a barber's fixture for illustrative purposes only, and this disclosure is not restrictive of the invention, as it is readily adaptable to other uses than the particular use herein disclosed. It is also to be understood that the supply pipes may be connected to the faucets 10 and the mixing chamber in any suitable manner and that if desired, the mixing chamber may be eliminated and the supply pipes deliver directly into the valve chamber, in which event the nipple 20 would be connected to the cock body above the partition therein. It is further to be understood that the invention may be embodied in a fixture for use in connection with sinks, in which event, the hose supporting device may be varied, as desired. My invention is susceptible of various other modifications and changes which would be within the spirit of the invention without departing from the scope of the following claims.

I claim:

1. A fixture of the class described comprising a hot water cock, a cold water cock, a mixing cock to which the aforementioned cocks deliver, a spout leading from said mixing cock, a spray tube nipple leading from said mixing cock, a valve in said mixing cock, a reciprocable plunger-type handle for said valve, and means for supporting the tube adjacent the mixing cock whereby the hand holding the tube may operate said valve without laterally directing the spray.

2. A fixture of the class described comprising a hot water cock, a cold water cock, a mixing cock to which the aforementioned cocks deliver, a spout leading from said mixing cock, a spray tube nipple leading from said mixing cock, a valve in said mixing cock, a reciprocable plunger-type handle for said valve, and a standard rising from said fixture adjacent the mixing cock, said standard carrying means for supporting the spray tube adjacent said mixing cock valve, whereby the hand holding the tube may operate said valve without laterally directing the spray.

3. A fixture of the class described, comprising a hot water cock, a cold water cock, a mixing cock to which the aforementioned cocks deliver, a spout leading from said mixing cock, a spray tube nipple leading from said mixing cock, a valve in said mixing cock, a vertically reciprocable plunger-type handle for said valve, and a standard rising from said fixture adjacent the mixing cock, said standard carrying means for supporting a spray tube adjacent said mix-

ing cock valve, whereby the hand holding the spray tube may operate the valve without laterally directing the spray.

4. A hot and cold water fixture of the 5 class described, comprising a spray nipple, a manually operable flexible tube connected to said spray nipple, a standard secured to said fixture and extending upwardly therefrom, a fork on said standard adapted to receive an intermediate portion of the 10 hose and support the latter, and a second fork intermediate said standard adapted to receive the free end of the hose.

5. A hot and cold water fixture of the 15 class described, comprising a spray nipple, a manually operable flexible tube connected to said spray nipple, a standard secured to said fixture and extending upwardly therefrom, a fork on said standard adapted to receive and support an intermediate portion 20 of the hose, said fork including a saddle member extending transversely thereof, and a second fork intermediate said standard adapted to receive the free end of the 25 hose.

6. A hot and cold water fixture of the class 30 described, comprising a spray nipple, a manually operable flexible hose connected to said spray nipple, a standard extending upwardly from said fixture and secured there-

to, a fork on the end of said standard having a saddle portion extending transversely thereof, and a second fork extending horizontally from the standard and adapted to receive the free end of the hose. 35

7. A hot and cold water fixture of the class 40 described, comprising a spray nipple, a flexible hose connected to said spray nipple, a standard rising from said fixture, a fork on the upper end of said standard, and a 45 bracket positioned on said standard having at one side of the latter an opening through which the tube is adapted to pass and at the other side of the standard a fork to receive the free end of the tube.

8. A hot and cold water fixture of the class 50 described comprising a spray nipple, a flexible hose connected to said spray nipple, a standard secured to and extending upwardly from said fixture, a bracket extending outwardly from the standard and having an eye through which the hose is adapted to pass, a hose rest at the upper end of said standard over which the hose is looped, and a fork intermediate the ends of said standard 55 adapted to receive the free end of the hose.

In testimony whereof I have hereunto set my hand.

PHILIP MUELLER.
